OTHER PUBLICATIONS

U.S. patent application Ser. No. D. 29/175,612, filed Feb. 7, 2003, 58285US002 3M'Docket No.—Tape Dispenser.

Primary Examiner—Martie K. Holtje

(74) Attorney, Agent, or Firm—George W Jonas

(57) **CLAIM**

The ornamental design for a desktop tape dispenser, as shown and described.

DESCRIPTION

FIG. 1 is a perspective view showing the new design for a desktop tape dispenser.

FIG. 2 is a left side view showing the new design for a desktop tape dispenser.

FIG. 3 is a right side view showing the new design for a desktop tape dispenser.

FIG. 4 is a bottom view showing the new design for a desktop tape dispenser

FIG. 5 is a top view showing the new design for a desktop tape dispenser

FIG. 6 is a front view showing the new design for a desktop tape dispenser; and,

FIG. 7 is a back view showing the new design for a desktop tape dispenser.

The structure depicted by means of broken lines in the figures has been shown for illustrative purposes only and forms no part of the claimed invention.

UNITED STATES PATENT AND TRADEMARK OFFICE
CERTIFICATE OF CORRECTION

PATENT NO. : Des. 496,690 S
DATED : September 28, 2004
INVENTOR(S) : Crawford, Dennis L.

Page 1 of 1

It is certified that error appears in the above-identified patent and that said Letters Patent is hereby corrected as shown below:

Title page,
Item [73], Assignee, delete “**Image**” and insert in place thereof -- **Innovative** --.

Signed and Sealed this

First Day of February, 2005

A handwritten signature in black ink, appearing to read "Jon W. Dudas". The signature is written in a cursive style with a large, stylized "J" at the beginning.

JON W. DUDAS
Director of the United States Patent and Trademark Office
